UNITED STATES PATENT OFFICE.

JESSE J. GILBERT, OF NEW YORK, N. Y.

DETERGENT.

SPECIFICATION forming part of Letters Patent No. 429,435, dated June 3, 1890.

Application filed September 9, 1889. Serial No. 323,454. (Specimens.)

To all whom it may concern:

Be it known that I, JESSE J. GILBERT, a citizen of the United States, residing in the city of New York, county and State of New York, have invented certain new and useful Improvements in Compounds for Cleaning Marble and other Stone, of which the following is such a full, clear, concise, and exact description as will enable others skilled in the art to 10 which my invention appertains to make and use the same.

My invention relates to composition particularly adapted for cleaning marble, but which may also be used upon other stones—as, for 15 example, slate and blue-stone—my object being to provide a cleansing compound which will remove dirt and stains and restore the original color and polish.

In preparing my compound I take six 20 pounds of muriatic acid, with which I mix one pound of borax and one pound of soapstone finely powdered. To this may also be added two ounces of alum and two ounces of sal-ammoniac. The proportions may be some- 25 what varied, what I consider essential being the mixture of the muriatic acid with the borax and soapstone. The compound can be applied with an ordinary scrubbing-brush,

and dirt, stains, and discolorations will rapidly disappear. Very rough portions of the 30 stone to be cleaned may be smoothed down and polished independently with pumice-stone, and a little powdered pumice-stone may be added to the mixture itself, if desired. I have also found that marble cleaned with my 35 compound retains its color better and will not turn yellow, as it is apt to when the ordinary cleaning compounds are used.

Having now described my invention, what I claim as new, and desire to secure by Letters 40 Patent, is—

1. The herein-described compound for cleaning marble, &c., consisting of a mixture of muriatic acid, borax, and soapstone, substantially in the proportions hereinbefore set 45 forth, and for the purpose specified.

2. The herein-described compound for cleaning marble, &c., consisting of a mixture of muriatic acid, borax, soapstone, alum, and sal-ammoniac, substantially in the proportions hereinbefore set forth, and for the purpose 50 specified.

JESSE J. GILBERT.
